United States Patent Office

Des. 204,781
Patented May 17, 1966

204,781

CUP

Herbert Jourdan Wanderer, 606 Cedar Ave., Elmhurst, Ill.

Filed Aug. 17, 1965, Ser. No. 86,616

Term of patent 14 years

(Cl. D44—9)

Fig. 1

Fig. 2

FIG. 1 is a side elevational view of a cup embodying my new design;

FIG. 2 is a fragmentary bottom plan view of the container shown in FIG. 1;

FIG. 3 is a side elevational view of a cup showing another form of my new design wherein an additional frusto-conical section is included at the bottom, as shown; and

FIG. 4 is a fragmentary bottom plan view of the container shown in FIG. 3.

A cup holder is shown in broken lines in FIGS. 1 and 3 for illustrative purposes only.

I claim:

The ornamental design for a cup, as shown and described.
